GARMENT HANGER

Leon H. Zenthen, 3241 Portland Ave.,
Minneapolis, Minn.

Filed Oct. 3, 1957, Ser. No. 688,030

1 Claim. (Cl. 223—95)

This invention relates broadly to garment hangers of the type from which individual garments are held suspended from a support and, more particularly, to a trouser and skirt hanger.

The principal object of this invention is to provide a trouser and skirt hanger that is capable of supporting a pair of trousers or a skirt, the said trousers by the cuffs thereof and, conversely, the skirt by its waist band in such a manner as to preserve said garments in their properly pressed condition.

Another object of this invention is to provide a hanger of the type described whereby the trousers may be suspended from each cuff portion thereof with compensation provided for slightly varied widths of cuffs.

Another object of this invention is to provide a hanger of the type described wherein said hanger is provided with garment protecting tip sections, said tip sections also further enhancing the garment gripping qualities of the hanger.

A still further object of this invention is to provide a hanger of the type described that is relatively simple and easy to manufacture with a minimum amount of tooling and die work and still maintaining a high degree of garment supporting efficiency.

A still further object of this invention is to provide a hanger of the type described that permits the hanging of garments on individual hangers in a minimum amount of space and which hangers themselves, when not supporting a garment, will occupy a minimum amount of space.

A still further object of this invention is to provide a garment hanger of tempered spring steel construction which, after assuming an initial set, will always maintain proper tension to securely support a garment—a distinct advantage over standard spring steel wire which takes a set each time it is compressed to engage a garment.

A still further object of the invention is to provide a garment hanger that engages the lower inside diameter of each trouser leg at its crease or the inside waist band of a skirt by spring tension and frictional contact.

A still further object of the invention is to provide a garment hanger wherein its tempered spring steel supporting members have an overall length greater than the inside diameter of that portion of a garment which they engage.

A still further object of this invention is to provide a garment hanger, particular reference being made to a trouser hanger of the type described, wherein said trouser, with or without upturned cuffs, is held suspended at its lower end or cuff portion, at the crease from within the leg portion of said trouser rather than from within the upturned cuff portion, each leg of said trouser and being individually so supported.

A still further object of the invention is to provide a hanger of the type described wherein said hanger in certain of its assembled forms is provided with a supporting hook member that is capable of being folded into an inoperative position to facilitate packaging and carrying when not in use.

These and other objects of the invention will become

2

apparent from the following specification and claims taken in conjunction with the appended drawings which form a part of this application and in which like characters indicate like parts throughout the several views.

5 To the above end, generally stated, the invention consists of the novel devices and combination of devices hereinafter described and defined in the claim.

Referring to the drawings:

Fig. 1 is a side elevational view of one form of the improved garment hanger;

Fig. 2 is an end elevational view of the same;

Fig. 3 is a side elevational view of a modification of the hanger shown in Fig. 1;

Fig. 4 is an end elevational view of the modified version shown in Fig. 3; and

Fig. 5 is a fragmentary section of a single garment engaging member as would be embodied in a skirt hanger and also showing one of the garment protecting tips on an enlarged scale.

15 20 It will be understood that in the interest of brevity and to avoid the repetitious use of words, the garment hanger referred to is of tempered spring steel construction for the reasons heretofore given in the objects of the invention.

25 With reference to the form of the invention shown in Figs. 1 and 2, the numeral 6 indicates a trouser cuff-engaging spring member formed of a single piece of spring steel wire, the outer end portions 7 of which lie in substantially a horizontal plane but which may be

30 slightly downwardly diverging relative to the true horizontal plane thereof. The central portion of the spring member 6 is bent upwardly at the exact longitudinal center of the said spring member 6 to form an inverted U that is flattened longitudinally throughout most of its

35 closed upper end portion as indicated by the numeral 8. A supporting hook 9 is formed of a single piece of flat metal. A clip 10 is formed in the parent metal of the lower end portion 10' of the hook 9, said clip being in the form of an inverted U wherein the upper and side

40 portions thereof perforate the metal of the lower end portion of the hook 9 and the upper end portion of the clip 10 is bent outwardly to form a tab 11, as will presently be described. A longitudinally disposed groove 12 of substantially the same diameter as the wire forming

45 the spring member 6 is formed in the inner opposing surfaces of the clip 10, and the adjacent surfaces 10' of the lower end portion of the hook 9. It will thus be seen that to assemble the hook member 9 to the garment-engaging spring member 6, it is only necessary to position the section 8 over the tab 11 of the hook 9 and snap the former into position in the longitudinal groove 12.

50 It will be understood that the material of which the hook 9 is formed will possess enough inherent resiliency to frictionally and securely hold the spring member 6 in the groove 12 and still permit axial rotation of the hook 9 on the section 8 of the spring member 6, whereby the hook portion thereof may be folded downwardly into the inverted U of the member 6 for storing and packaging in a minimum amount of space. A radial bead 13 is

55 stamped or otherwise formed in the hook proper of the member 9 to impart greater rigidity and stiffness thereto. A pair of trouser-cuff-engaging members 14, see Figs. 1 and 2, are frictionally mounted on the outer end portion of the spring member 6 and have axial rotation therewith for minor adjustment with a garment supported

60 65 70 therefrom. These members are formed of a single piece of skeletonized material to achieve lightness of weight and are covered over most of their surfaces with a protective coating to afford protection for garments engaged thereby and to further enhance the gripping quality of the said members when the same engage the garment material. A plurality of transverse slits are formed at the

longitudinal center of the member 14 to afford upper and lower bearing members 15 which encircle the outer end portion of the spring member 6 with a relatively tight frictional fit. It is important to note here that the material outwardly of the outermost slit or cut is bent only to a point whereby it engages the transverse center of the end portions of the spring member 6 to afford a stop to limit the inward longitudinal movement of the members 14. The identical end portions of the said members 14 are thence bent downwardly until they are substantially parallel, to thus provide a pair of trouser-cuff-engaging fingers. These members 14 are so fabricated that when the same are bent into final position as above, its trouser-cuff-engaging fingers are in a downwardly and outwardly diverging place to facilitate the engagement of the same with the trouser cuff.

The parallel downturned members 14 being transversely spaced engage the cuff of each trouser leg with each longitudinally opposed pair thereof. To suspend a pair of trousers therefrom, it is only necessary to grip the centrally disposed inverted U section of the spring member 6 manually and thereby compress the same until the respective downturned fingers of the members 14 can be placed inside the cuff of the respective trouser leg at the crease. Thence, upon releasing the tension of the spring member 6, the members 14 mounted thereon will be expanded into engagement with the inside of the trouser cuff and tightly hold the same suspended therefrom.

It is desired to note here that the foregoing description of a trouser hanger will obviously suffice for a skirt hanger except that the dual parallel downturned prongs or fingers 14 for engagement with a pair of trouser cuffs are unnecessary. In a skirt hanger, the end portions of the spring member 6 are bent downwardly and outwardly to form a pair of downturned single prongs 16, as shown in Fig. 5, which, when compressed by manual pressure on the inverted U-shaped section of the spring member 6, are inserted inside the waist band of a skirt and thence released to expand outwardly against the restriction imposed by said waist band. A protective coating 17 is applied to the prongs 16 to further facilitate the expansive gripping qualities of the hanger and to protect the garment suspended therefrom.

The structure for both the trouser and skirt hanger thus far described has embodied the use of a single spring steel supporting arm or member 6 detachably connected to a hook member 9 and taken in a general sense, has proven to be entirely adequate for the purposes intended. It is well-known, however, that a certain variance occurs in the manufacture of trousers, slacks and the like and to compensate therefor I have provided a modification of the basic invention heretofore described, reference being had to the trouser hanger only.

It will be understood that when there is even a relatively slight variance in the width of the cuff of respective trouser leg portions, it is inevitable that the spring action of the hanger, expanded outwardly against the restriction of the respective cuffs, will engage said cuffs with a different degree of outward expansion. This condition must obviously occur when a single spring steel supporting member is used to mount the pairs of parallel downwardly projecting prongs 16. To meet the problem of trouser cuffs having somewhat varied widths, I have provided the following modification, as shown in Figs. 3 and 4 of the drawing.

In the interest of clarity, a prime (') will be used in connection with identical parts in Figs. 3 and 4 as previously described. In this modification, the hook member 9' is essentially the same except that the clip portion thereof 10' is transversely widened to accommodate a pair of spring steel supporting arms, each having a longitudinally disposed upwardly projected central U section 8', said U-sections at their respective upper edge or closed portion closely abutting one another in a horizontal plane, see numeral 18, Figs. 3-4, and thus held positioned by

grooves formed in the clip 10' and the clamping tab or fingerpiece 11'.

Formed in the lower end portion of the hook member 9' are a pair of opposed longitudinally extended ears 18' that extend between the spring members 6' in the upper or closed end portion of the U-section 8', thus affording a spacer member so positioned and dimensioned as to provide adequate separation progressively, to the outer end portions of the spring steel arm members 6' to facilitate the engagement of the same with the cuffs of a pair of trousers. The outer end portion of the independently acting spring steel members 6' are downturned to form a pair of cuff engaging prongs 14', each prong being coated with a material to protect the garment from metal contact and further enhance the frictional engaging qualities of the prongs 14' as they engage the inside of a trouser cuff.

It will thus be seen that a pair of independently acting spring members 6' will engage a single trouser cuff regardless of variance in the width of said cuffs and hold said trousers properly and tightly suspended relative to the crease therein. Obviously, in the modification just described, the assembled parts provide a very rigid structure and said modification does not lend itself to compact storing and packaging in assembled relation as does the unit having the single spring steel arm 6 and wherein the hook member 9 may be swung downwardly by axial rotation of the hook around the closed U portion of the hanger. However, one of the important features both from a sales and manufacturing standpoint of this improved hanger resides in its ability to be completely disassembled or assembled merely by holding the tab 11 or 11' open and separating the spring arm member 6 and 6' from the hook member 9-9' particularly for packaging.

While there are herein disclosed but a limited number of embodiments of the structure, process and product of the invention herein presented, it is possible to produce still other embodiments without departing from the inventive concept herein disclosed, and it is desired, therefore, that only such limitations be imposed on the appended claim as are stated herein or required by the prior art.

What I claim is:

45 A garment hanger of the class described comprising in combination, a supporting hook member, a pair of spring steel garment supporting members having parallel central portions, outwardly and downwardly extending intermediate portions and outwardly and longitudinally extending garment supporting arms terminating at their respective outer end portions in pairs of opposed and laterally spaced downturned garment engaging prongs, clamping means associated and integral with the said hook member for clamping the central portions of the garment supporting members in operable arrangement, spacer means integral with and depending from the clamping means of the hook member interposed between the spring steel garment supporting members at the central portions thereof whereby the said garment supporting members and the garment supporting prongs are held in progressive outwardly and downwardly spaced arrangement the one from the other to facilitate the mounting of a garment thereon, each garment supporting arm and its cooperating garment engaging prong being mounted to independently engage a portion of a garment supported thereon.
